UNITED STATES PATENT OFFICE

LAWRENCE R. EDDY, OF MANASQUAN, NEW JERSEY

PIN CUSHION FOR SPOOLS

Application filed May 2, 1928. Serial No. 274,648.

This invention relates to improvements in needle and pin cushions, especially adapted for use in combination with cotton and silk spools of the usual type, and has for its object 5 to provide a cushion which is detachable from the spool and wherein the pad portion can be renewed when desired.

These and other objects hereinafter set forth are attained by the means illustrated 10 in the accompanying drawing, in which:

Figure 1 is a side elevation of the device affixed to a spool of thread.

Figure 2 is a vertical sectional view of Figure 1.

15 Figure 3 is a side elevation of the pad holder portion of the device showing the fabric cover in the manner it appears when first inserted in the holder.

20 Figure 4 is a perspective separated view of the cushion showing the fabric cover with its long skirt portion cut off.

Figure 5 is a vertical sectional view showing a modified form of pad holder.

25 Similar reference numerals in all of the figures of the drawing designate like parts.

Referring to the drawing, 10 designates a holding base preferably constructed in the shape of a cup having its upstanding flange 11 extending entirely around the edge thereof, 30 and said holding base is provided with a pair of spring fingers 12, which are adapted to be inserted within the base of a spool and each finger is provided with an outwardly projecting hump 13, which are adapted to frictionally engage the sides of the base of the spool, and thus retain the holding base in position upon the end of the spool. The spring fingers 12 are preferably soldered to the bottom of the base, as shown in the drawing, 40 but it will be understood that said fingers may be made shorter and stamped from the bottom of the base, thus making them integral therewith.

45 Adapted to be contained in the holding base 10-11 is a cushion holding cup 14, the base plate or bottom 15 of which is provided with a central aperture the surrounding wall of which is formed with a series of teeth 16 which are adapted to engage the skirt portion 50 of the fabric cover 17 and thus retain it

and its cushion filler 18 in position with the cup portion of the cushion holder. The cushion filler may consist of any cotton-wool, hair, or any other soft material into which can be inserted pins or needles, or the filling 55 may be emery powder, if desired. If emery-powder is used, the base of the holding cup 10 is preferably made solid across its base to prevent sifting of the powder through the 60 base of the spool.

The base of the holding cup 10 is provided with several apertures 19 through which can be inserted a nail or other instrument by which the cushion holding cup can be displaced when it is desired to renew the cushion 65 cover or its contents. The holes 19 are preferably arranged at diametric points in the base so that an instrument inserted therethrough will engage the base of the cushion cup near its edge, and by thus positioning 70 said holes, they will be far removed from the central opening of the cushion cup and thus prevent the loss of emery-powder through the holding cup base.

75 The method of inserting the cushion member in its cup, consists of folding a sheet of fabric around a mass of filling material and twisting the free edges of the fabric at one side of the filling mass, it being preferable to use a sufficiently large sheet of fabric, so 80 that it can be easily twisted to form the ball-shaped cushion, and by using the relatively large sheets of fabric, it enables the operator to easily thread the long twisted end through the central aperture of the cushion holder, also pull the ball cushion tightly into the cup, and finally spreading the twisted portion of the fabric into engagement with the teeth 85 16 and thus lock the fabric tightly in position.

90 Before inserting the cushion cup 14 in its holding base 10, the long skirt portion 20, shown in Figure 3, is first cut off or shortened, as shown in Figure 4, so that when the two 95 cups are assembled, the short skirt of the fabric will spread over the top side of the holding cup base and be confined tightly between the bases of the two cups, it being understood that the cup 14 is of a size to fric- 100

tionally fit within the cup 10, so that it can-
not be accidentally displaced in handling.

In the modified form shown in Figure 5,
the cushion cup is formed with an outer flange
21, which is adapted to cover the flange 11
of the holding cup, and in this form this
outer flange can be grasped by the fingers to
remove the cushion cup, thereby avoiding the
use of the holes 19.

10 Having thus fully described the invention,
what is claimed is:—

A pin cushion comprising a cushion having
a fabric covering for retaining its filling, a
holder for said cushion having an upstand-
ing flange and means for detachably holding
the free edge of said fabric covering, a hold-
ing cup for detachably supporting the flanged
cushion holder, said holding cup being pro-
vided with means for detachably connecting
it to a spool, and apertures in the base there-
of to permit the insertion of a suitable tool
to force the cushion holder free from the
holding cup.

15 In testimony whereof I affix my signature.
